VALVE PULLING TOOL

Ezekiel Seminario, 15500 Tustin Village Way,
Tustin, Calif. 92680

Filed Dec. 21, 1973, Ser. No. 427,207

Term of patent 14 years

Int. Cl. D8—05

U.S. Cl. D8—59

FIG. 1 is a pictorial view of my new valve pulling tool;
FIG. 2 is a top plan view thereof;

FIG. 3 is a view in side elevation thereof;
FIG. 4 is a bottom plan view thereof; and
FIG. 5 is a view in end elevation thereof.

I claim:

The ornamental design for a valve pulling tool, as
shown.
